FISHING POLE HOLDER

Robert G. Nelson, 23206 U.S. 20,
South Bend, Ind. 46628

Filed Dec. 6, 1972, Ser. No. 312,598

Term of patent 14 years

Int. Cl. D22—05

U.S. Cl. D22—22

Fig. 1

Fig. 3

FIG. 1 is a perspective view of a fishing pole holder embodying the present design;

FIG. 2 is an elevational view of the side of the fishing pole holder opposite that shown in FIG. 1;

FIG. 3 is a rear elevational view of the fishing pole holder shown in the preceding figures;

FIG. 4 is a front elevational view thereof;

FIG. 5 is a top plan view thereof; and

FIG. 6 is a bottom plan view thereof.

I claim:

The ornamental design for a fishing pole holder, substantially as shown.
